UNITED STATES PATENT OFFICE.

CHARLES H. STEPHENSON, OF LYNN, MASSACHUSETTS.

GARBAGE-RECEPTACLE CONTAINER.

No. 868,894.

Specification of Letters Patent.

Patented Oct. 22, 1907.

Application filed July 3, 1905. Serial No. 268,244.

To all whom it may concern:

Be it known that I, CHARLES H. STEPHENSON, of Lynn, in the county of Essex and State of Massachusetts, have invented certain new and useful Improvements in Garbage-Receptacle Containers, of which the following is a specification.

This invention relates to receptacles for garbage, which term is intended to include waste matter of various kinds, and not only household refuse but also sweepings of streets, platforms, etc., and other refuse matter.

The class of garbage-holders to which my invention relates comprises a fixed container adapted to be placed in an opening in the ground or otherwise supported, and a portable garbage-holder adapted to be inserted in the container, the latter being provided with a hinged primary cover, which when open permits the insertion and removal of the garbage-holder, the primary cover having an opening inclosed by a secondary cover, which when open permits refuse matter to be deposited in the holder without opening the primary cover. An apparatus of this character is shown in Letters Patent of the United States No. 722,766, granted to me March 17, 1903.

The present invention consists in the improvements which I will now proceed to describe and claim.

Of the accompanying drawings, forming a part of this specification,—Figure 1 represents a sectional view of a container embodying my invention. Fig. 2 represents an enlargement of a portion of Fig. 1. Fig. 3 represents a fragmentary perspective view. Figs. 4 and 5 represent sectional views of modifications. Fig. 6 represents a fragmentary perspective view. Fig. 7 represents a section on line 7—7 Fig. 6.

The same reference characters indicate the same parts in all the figures.

In the drawings,—12 represents the container-body, which is a cylinder of sheet metal, having wire reinforcing-rings 13 and 14 at its ends, the sheet metal being rolled outwardly over the top ring 13, and preferably rolled inwardly over the bottom ring 14, the inwardly rolled portion constituting a seat for a spider 15 which supports the portable holder 16.

17 represents the primary cover, which is composed of sheet metal and has a wire reinforcing-ring 18 at its outer edge, the margin of the sheet-metal cover-body being rolled over the ring, which is of greater diameter than the mouth of the container, so that the reinforced edge of the cover forms a downwardly projecting lip or flange, which surrounds the mouth of the container and prevents the entrance of rain and snow between the cover and the container. The cover has a central opening for the reception of garbage, said opening being rounded by a chute 19, which guides the garbage into the holder 16. The chute is also of sheet metal, and in the construction shown in Fig. 1, is integral with the

body of the cover, the latter being bent upwardly to form an annular ridge 20, which constitutes a seat for the secondary cover 21. A wire reinforcing-ring 22 is inserted in said ridge, and secured by solder or otherwise. 60

In Fig. 4, the chute 19 is shown as a separate sheet-metal tube, rolled outwardly at its upper end over a wire reinforcing-ring 23. The cover is a sheet-metal annulus bent upwardly at its inner margin to form a flange 24, which enters the crevice formed by the outwardly rolled end of the chute, and may be soldered or otherwise secured to the latter.

The primary cover is connected with the container by a hinge, preferably made of wire, and formed as shown in Fig. 3, said hinge including arms 25 which are soldered or otherwise secured to the under side of the cover, and eyes 26 which embrace the container-reinforcing ring 13, slots 27 being cut in the sheet-metal body of the container, for the reception of the eyes. A single piece of wire is employed in the construction of the hinge, the central portion of the piece constituting a cross-bar 28 connecting the eyes 26, while the ends 29 are or may be bent inwardly and secured with the arms 25, to the cover. The secondary cover 21 is also made of a disk of sheet metal, which is 80 rolled at its margin over a wire reinforcing-ring 30, said reinforced margin forming a downwardly projecting lip or flange, which is of greater diameter than the cover-seat or ridge 20, and surrounds the latter to prevent the entrance of rain and snow. The secondary 85 cover is connected with the primary cover by a hinge composed of a metal strip riveted to the primary cover and bent to form an eye 31, which is engaged either with the reinforcing-ring 22, as shown in Figs. 1 and 2, or with the reinforcing-ring 23, as shown in Fig. 4, a 90 suitable opening being formed for the reception of said eye, in the sheet metal which covers the reinforcing-ring.

It will be seen that the above-described construction enables sheet metal to be advantageously employed as the material of the container and its covers, and provides for suitable strength and durability, as well as for the exclusion of water from the container. 95

In Fig. 5, I show the primary cover provided with a downwardly projecting flange 33 adapted to enter 100 the mouth of the container.

In Figs. 6 and 7 I show the holder 16 provided with a handle composed of a stout metal rod bent to form a hand grip 300, arms 310 at the ends of the grip, and eyes 320 at the ends of the arms. The eyes 320 surround a bead 240 at the upper end of the holder 16, and a reinforcing ring within said holder, orifices 330 being formed in the sheet metal body of the holder below said bead to receive the lower portions of the eyes. A strong and durable handle is thus provided which is 105 adapted to swing downwardly over the interior of the holder when not in use, so that it is out of the way and 110

not liable to be injured by contact with external objects.

I claim:

5. A sheet-metal container having a reinforcing-ring forming an uninterrupted circle at its upper end, and a cover having a hinge engaged with the ring, the hinge being located entirely within the margin of the cover.
10. A sheet-metal container having a hinge-pintle member at its upper end, and a cover having a wire hinge comprising arms affixed to the cover, and spaced eyes engaged with the pintle member, the hinge being located entirely within the margin of the cover.
15. A sheet-metal container having a reinforcing-ring forming an uninterrupted circle at its upper end, and a cover having a wire hinge comprising arms affixed to the cover, and eyes engaged with the ring.
20. A sheet-metal primary cover having a central opening, a chute surrounding said opening and extending below the plane of the cover, a hollow ridge or raised seat surrounding the chute, and a secondary cover formed to bear on said seat.
25. A sheet-metal primary cover having a central open-

ing, a chute surrounding the opening, a ridge or raised seat surrounding the chute and having a reinforcing ring, and a secondary cover having a hinge engaged with said ring. 25

6. A sheet-metal container-cover having a reinforced margin forming a downwardly projecting lip or flange, a hollow ridge or raised seat surrounding a central opening, and a sheet-metal secondary cover having a reinforced margin formed to surround and project below said seat. 30

7. A sheet metal receptacle having a primary cover formed with an opening and having a vertical cylindrical chute extending downward from said opening, the cover seat being formed at the upper portion of said chute, and a secondary cover hinged to the primary cover and adapted to close said opening, said secondary cover having its margin surrounding and projecting below the plane of said seat. 35

In testimony whereof I have affixed my signature, in presence of two witnesses.

CHARLES H. STEPHENSON.
